US00D794789S

(12) **United States Design Patent** (10) **Patent No.:** **US D794,789 S**
(45) **Date of Patent:** **** Aug. 15, 2017**

(54) **ELECTROSURGICAL FORCEPS**

- (71) Applicant: **Kirwan Surgical Products LLC**,
Marshfield, MA (US)
- (72) Inventors: **Lawrence T. Kirwan, Jr.**, Kingston,
MA (US); **Robert T. Boyd**, Kingston,
MA (US); **Aaron Cohen-Gadol**,
Indianapolis, IN (US)
- (73) Assignee: **Kirwan Surgical Products LLC**,
Marshfield, MA (US)
- (**) Term: **15 Years**
- (21) Appl. No.: **29/580,002**
- (22) Filed: **Oct. 5, 2016**

(57) **CLAIM**

The ornamental design for an electrosurgical forceps, as shown and described.

DESCRIPTION

FIG. 1 is a perspective view of an electrosurgical forceps. FIG. 2 is a top plan view of the electrosurgical forceps of FIG. 1.

FIG. 3 is a bottom plan view of the electrosurgical forceps of FIG. 1.

FIG. 4 is a right side elevation view of the electrosurgical forceps of FIG. 1.

FIG. 5 is a left side elevation view of the electrosurgical forceps of FIG. 1.

FIG. 6 is a distal end elevation view of the electrosurgical forceps of FIG. 1.

FIG. 7 is a proximal end elevation view of the electrosurgical forceps of FIG. 1.

FIG. 8 is a top plan view of a variant of the electrosurgical forceps of FIG. 1 having a shorter blade length; and, FIG. 9 is a top plan view of a variant of the electrosurgical forceps of FIG. 1 having a longer blade length.

1 Claim, 4 Drawing Sheets
